CLAIM

The ornamental design for an distance measuring device, as shown and described.

DESCRIPTION

FIG. 1 is a top, front, left side perspective view of a distance measuring device showing my new design;

FIG. 2 is a top, rear, left side perspective view thereof;

FIG. 3 is an enlarged front elevation view thereof;

FIG. 4 is an enlarged rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings illustrate portions of the distance measuring device that form no part of the claimed design.

1 Claim, 8 Drawing Sheets(56)
